CARGO TRAILER

L. Ray Wood, 501 Circle Drive, Arlington, Tex. 76011

Filed Nov. 1, 1972, Ser. No. 302,945

Term of patent 7 years

Int. Cl. D12—10

U.S. Cl. D14—3 E

FIG. 1

FIG. 2

FIG. 3

FIG. 4

FIG. 5

FIG. 6

FIG. 7

FIG. 8

FIG. 1 is a top plan view of a cargo trailer showing my new design;

FIG. 2 is a right side elevational view;

FIG. 3 is a bottom plan view;

FIG. 4 is a rear elevational view;

FIG. 5 is a front elevational view;

FIG. 6 is a left side elevational view;

FIG. 7 is a perspective view taken from the left rear corner, with the rear door shown in its open position; and

FIG. 8 is an enlarged fragmentary perspective view thereof of the lower left rear corner with an arm which is used in maneuvering the cargo trailer to a parked aircraft, shown in its extended position.

I claim:

The ornamental design for a cargo trailer, as shown and described.
